DESIGN FOR A CLOCK

Alexander R. Tigerman and Milton N. Tigerman,
Chicago, Ill.

Application April 18, 1941, Serial No. 100,495

Term of patent 7 years

To all whom it may concern:

Be it known that we, Alexander R. Tigerman and Milton N. Tigerman, both citizens of the United States, residing at Chicago, Cook County, Illinois, have invented a new, original, and ornamental Design for a Clock, of which the following is a specification, reference being had to the accompanying drawing, forming part thereof.

Figure 1 is a perspective view of a clock, showing our new design; and

Figure 2 is a side elevation of the clock.

The numerals which appear in the openings in both figures are merely representative.

We claim:

The ornamental design for a clock, as shown and described.

ALEXANDER R. TIGERMAN.
MILTON N. TIGERMAN.
